UNITED STATES PATENT OFFICE.

ALONZO L. EDWARDS, OF WHEELING, WEST VIRGINIA, ASSIGNOR TO WHEELING STAMPING COMPANY, OF WHEELING, WEST VIRGINIA, A CORPORATION OF WEST VIRGINIA.

GLASS-CONE BURNER.

No. 914,249.

Specification of Letters Patent.

Patented March 2, 1909.

Application filed December 24, 1907. Serial No. 407,986.

To all whom it may concern:

Be it known that I, ALONZO L. EDWARDS, of Wheeling, Ohio county, West Virginia, have invented a new and useful Glass-Cone Burner, of which the following is a full, clear, and exact description, reference being had to the accompanying drawings, forming part of this specification, in which—

Figure 1 is a side elevation showing a burner constructed in accordance with my invention; Fig. 2 is a partial vertical section; and Fig. 3 is a partial sectional view showing one of the bent clips. Fig. 4 is a detail view showing a modification.

15 My invention relates to the class of glass cone burners, and is designed to provide a simple, cheap and efficient means for holding the glass cone in position.

In the drawings, I show the glass cone as made in two halves 2, 2, divided at the center of the plane of the flame slot. The cone is provided with an external circumferential rib 3, which is adapted to be inserted from above and sprung into the spring clips 4 of the 25 hinged holding ring 5. This brass ring may have four or any desired number of these spring clips, which have inclined extensions 6, and this ring is preferably provided with shorter holding clips 7 which are bent over 30 into engagement with the rib after the cone is sprung into the spring clips. These bent clips may engage either the rib, or may enter recesses formed in the rib or the glass as shown at 8, Fig. 4. The frictional resistance,

however, of the clips as shown is sufficient to 35 prevent rotation of the burner as well as hold it in its desired place. The holding ring is preferably hinged to the burner, and the ring and burner may be of any desired type.

The advantages of my invention result 40 from the use of the spring clips and bent clips, which afford a simple, neat and attractive holder for the glass cone.

Variations may be made in the form and arrangement of the cone, which may be made 45 in one or more parts, as well as in the ring and burner, without departing from my invention.

I claim:—

In a glass cone burner, a burner ring, and a 50 cone arranged to be seated in said ring from above, and having a circumferential rib above its lower end and which seats against the upper edge of the ring, said ring having spring clips arranged to spring over the said 55 rib, to hold the cone against vertical displacement, and smaller bendable lugs between the clips adapted to be forced into engagement with said rib to hold the cone from rotary displacement with reference to the 60 wick tube of the burner; substantially as described.

In testimony whereof, I have hereunto set my hand.

ALONZO L. EDWARDS.
